UNITED STATES PATENT OFFICE.

DAVID FRISHMAN, OF NEW YORK, N. Y.

DESIGN FOR AN ASH-HOLDER.

•56,591.

Specification for Design. Patented Nov. 16, 1920.

Application filed March 9, 1920. Serial No. 364,523. Term of patent 7 years.

To all whom it may concern:

Be it known that I, DAVID FRISHMAN, a citizen of the United States, and residing at New York, New York county, and New York State, have invented a new, original, and ornamental Design for an Ash-Holder, of which the following is a specification, reference being had to the accompanying drawing, forming a part thereof, and in which—

Fig. 2 is a plan view of the same.

What I claim is:

The ornamental design for an ash holder, as shown.

In testimony whereof, I have signed my name to this specification in the presence of two subscribing witnesses, this 20th day of February, 1920.

DAVID FRISHMAN.

Witnesses:

A. W. BAKER,
JAMES F. DUHAMEL.
